US00D931560S

(12) **United States Design Patent** (10) **Patent No.:** **US D931,560 S**
(45) **Date of Patent:** **** Sep. 21, 2021**

(54) **PRESSURE WASHER**

(71) Applicant: **Ningbo Yinzhou Jiasheng Pump Electric Machinery Factory, Ningbo (CN)**

(72) Inventor: **Rong-Ding Xu, Ningbo (CN)**

(73) Assignee: **Ningbo Yinzhou Jiasheng Pump Electric Machinery Factory, Ningbo (CN)**

(**) Term: **15 Years**

(21) Appl. No.: **29/678,639**

(22) Filed: **Jan. 30, 2019**

(51) LOC (13) Cl. **15-05**

(52) U.S. Cl. **USPC D32/16**

(58) **Field of Classification Search**

USPC D32/15-16
CPC B05B 9/04; B05B 7/24
See application file for complete search history.

(57) **CLAIM**

The ornamental design for a pressure washer, as shown and described.

DESCRIPTION

FIG. 1 is a front, bottom, left side perspective view of my design for a pressure washer;

FIG. 2 is a rear, top, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the pressure washer that form no part of the claimed design.

1 Claim, 8 Drawing Sheets
